UNITED STATES PATENT OFFICE.

PIETRO P. VESCOVI, OF ARMA, KANSAS.

FIRE ESCAPE.

Application filed September 30, 1921. Serial No. 504,325.

To all whom it may concern:

Be it known that I, PIETRO P. Vescovi, a subject of the King of Italy, residing at Arma, in the county of Crawford and State 5 of Kansas, United States of America, have invented certain new and useful Improvements in Fire Escapes; and I do declare the following to be a full, clear, and exact description of the invention, such as will enable others skilled in the art to which it 10 pertains to make and use the same, reference being had to the accompanying drawings, and to the figures of reference marked thereon, which form a part of this specification.

This invention relates to portable fire escapes, the primary object being to provide an inexpensive, easily operated, efficient fire escape adapted to be also used as an elevator 20 whereby persons may manually operate the device to elevate themselves from mine shafts and the like.

The invention broadly contemplates a mechanism adapted to be confined within a 25 relatively small compass and it includes a flexible member adapted to be wound upon and unwound from a spindle within a drum or casing, one end of the flexible member being anchored to a suitable support so as 30 to permit the flexible member to be gradually wound or unwound upon the spindle as the person ascends or descends, the unwinding of the flexible connection or member being induced by the weight of the person 35 there being mechanically applied braking means so that the rate of descent can be controlled by the person descending.

In the drawings,

Fig. 1 is a perspective view of a fire escape 40 constructed in accordance with my invention, part of the casing being broken away to show the brake band applicator and part of the band.

Fig. 2 is a sectional view on the line 2—2 45 of Fig. 1, and

Fig. 3 is a fragmentary perspective view of certain braking means for the flexible connection.

The casing 1 is shown as substantially cy- 50 lindrical, having a removable cover 2 with an inner flange 3, by means of which the cover can be fastened to the peripheral flange 4, by fastening devices 5. The cover carries a bridging strap 6, having a spindle 55 or shaft bearing 7 aligning with a corresponding bearing 8 in the casing. The bear-

ings 7 and 8 support a transverse shaft or spindle 9, on which is mounted a brake drum 10, the drum having a hub portion 11 extending beyond the drum proper and constituting means for engagement with the inner end of a coiled flexible tape 12, which is wound about the same to form a coil beside the brake drum and within the casing 1.

The flexible connection or tape has a free 65 end which travels through the slots 13 and 14 in the casing, over the rigid friction face or bar 15 carried by the flange 4 and adapted to be adjustably and frictionally engaged by a brake shoe 16, actuated by a thumb nut 70 17 passing through the support or bridge piece 18, bridging the friction member 15 and the slots 13 and 14, as clearly seen in Figs. 1 and 3.

By reference to Fig. 3 it will be seen that 75 the tape 12 passes from the casing through the slot 13 and back into the casing through the slot 14 and that it then passes out through the slot 19 bounded by the box-shaped flange 20 so that its free end or loop 80 21 may engage a hook or other support, by means of which the fire escape may be suspended.

The side walls 22 and 23 of the box-shaped flange 20 support a pivot 24, upon 85 which is mounted a double toothed friction dog or braking member 25, the ends 26 and 27 being faced with braking material to bear against the face of the tape and retard the descent or unwinding action of the tape. 90 This dog will exert a certain resistance to the descent of the casing when a person is suspended therefrom through the medium of the loop 28 on the flange 4 (see Fig. 1). The resistance of the unwinding action of the 95 tape can be controlled by the thumb nut 17.

By reference to Fig. 2 it will be observed that the diameter of the brake drum is only slightly less than the diameter of the casing, the peripheral flange 29 being spaced 100 from the flange 4 to provide a brake band space 30. The brake band 31 has outstanding ends 32 and 33 projecting through the slot 33 in the circumferential flange 4. The end 32 of the brake band is perforated at 105 to loosely receive the unthreaded portion of the draw screw 35 which passes through the end of the strap 36 bridging the slot 33. The end 38 of the brake band loosely receives the threaded end of the draw screw 110 35. There is a nut 37 upon the threaded end of the draw screw 35 between the end 38

of the brake band and the end of the strap distant from the end 39. By reference to Fig. 1 it will be seen that there is a handle or actuator 41 on the end of the draw screw 5 which projects through the end 39, and that the nut cannot turn due to the fact that one side bears against the strap 36. Therefore, if the operator turns the actuator 41 in one direction through the medium of the handle 42, the screw 35 will act as a draw screw on the nut 37 and draw the end 38 toward the end 32 of the brake band 31, tightening the band on the perimeter of the brake drum 10, thereby resisting the unwinding movement of the spindle or shaft 9 because the brake drum and the end of the flexible connection 12 are both fastened to the shaft 9.

10 The thumb nut 17 and the actuator 41 may be operated simultaneously to exert frictional resistance to both the drum and the tape so that one braking means will augment the other to effect efficient resistance against the unwinding movement of the flexible connection or tape 12 and this resistance can be in proportion to the weight of the person suspended from the loop 28.

15 Any means can be provided for attachment to the loop 28; for example, a hook or belt to go around the waist of the person, a harness can be supplied or a sling may be suspended.

20 When the fire escape is to be used, the person to be lowered will see that the loop 21 is hooked over a suitable support and he may then lower himself from a window or other opening, permitting the flexible band or tape 12 to unwind. The dog 25 will offer an initial resistance to the unwinding of the tape and the person being lowered can manipulate both the wing nut and the actuator 41 to provide the necessary friction against the tape and the brake drum respectively so that the rate of descent can be controlled.

25 In the event that the device is to be used as an elevator, for example, in case of a mine disaster or where it is desired to assist a person to ascend from a well or shaft, the loop 21 can engage a hook and the device can be unwound and lowered into the well, shaft or cavern. The operator will then effect a connection with the loop 28 and reverse the operation; that is, wind the tape upon the spindle or shaft 9. In order to facilitate the winding operation I have provided a reduction gearing consisting of a gear 43 rigid on the shaft or spindle 9 and meshing with a pinion 44 on a crank shaft 45, journaled in the bearings 46 and 47 in the cover 2 and strap 6 respectively. The 30 handle 48 of the crank can be grasped by the operator and by turning the same, the tape will be wound upon the shaft or spindle 9 so that the person operating it will be caused to ascend to the top of the well or shaft, as 35 the case may be.

From the foregoing it will be apparent that the fire escape can be confined within a relatively small space and it can be efficiently operated to control the rate of descent of a person supported thereby, as well as to serve as an elevator for assisting persons in ascending whenever expedient.

What I claim and desire to secure by Letters-Patent is:

1. A portable fire escape comprising a 75 casing, a rotatable shaft in said casing, a flexible member coiled about the shaft and having an end projecting through a slot in the casing, the end of the flexible member being threaded back into a parallel slot and 80 over an intermediate portion of the casing to provide a friction surface, the final end of the flexible member extending outwardly through a slot in the casing, a brake shoe supported above the flexible member between 85 the first two slots, and means for varyingly applying pressure to the brake shoe to frictionally engage the flexible member.

2. A portable fire escape comprising a cylindrical casing, a shaft concentrically 90 mounted in said casing, a brake drum mounted on said shaft within the casing, the brake drum being of less diameter than that of the casing to provide a brake band space between the perimeter of the drum and the 95 casing, the brake band having free ends extending through a slot in the casing, the ends extending outwardly and substantially parallel one with the other, a strap connected to the casing and bridging the ends 100 of the brake band and extending over the slot, a draw screw rotatable in the strap, a nut loose on the draw screw and interposed between one end of the strap and one end of the brake band, a handle integral 105 with the draw screw whereby upon turning the handle the draw screw will impart a longitudinal movement to the nut to draw the ends of the brake band together to cause the band to bind against the drum, and a 110 flexible tape coil about the shaft, and having one end projecting through a slot in the casing.

3. A portable fire escape comprising a cylindrical casing, a shaft concentrically 115 mounted in said casing, a brake drum mounted on said shaft within the casing, the brake drum being of less diameter than that of the casing to provide a brake band space between the perimeter of the drum and the casing, the brake band having free parallel ends extending through a slot in the casing, a strap connected to the casing and bridging the ends of the brake band and slot, a draw screw rotatable in the 120 strap, a nut loose on the draw screw and mounted for longitudinal movement with respect thereto, but held against rotatable movement with respect thereto, the nut 125 when moving in one direction exerting force 130

against one end of the brake band to lessen the space between the two brake band ends, a handle on the draw screw, whereby, upon turning the handle the draw screw will cause the nut to have longitudinal movement to draw one end of the brake band toward the other to cause the brake band to bind against the drum, a flexible tape having a

free end threaded outwardly and inwardly through parallel slots in the casing, and then outwardly through another slot in the casing, and an auxiliary braking means having variable frictional contact with said tape between the first two slots.

In testimony whereof I affix my signature. 15
PIETRO P. VESCOVI.
